PLANETARIUM

Clair Omar Musser, 12997 Blairwood Drive,
Studio City, Calif. 91604

Filed Nov. 9, 1966, Ser. No. 4,593

Term of patent 14 years

(Cl. D25—1)

FIG. 1.

FIG. 2.

FIG. 3.

FIG.4.

FIG. 5.

FIG. 6.

FIG. 7.

FIG. 8.

FIG. 1 is a front elevational view of a planetarium showing my new design;

FIG. 2 is a right side elevational view thereof; the left side being essentially the same;

FIG. 3 is a top plan view thereof;

FIG. 4 is a top plan view with the dome removed;

FIG. 5 is a bottom plan view thereof on a reduced scale;

FIG. 6 is a front elevational view of FIG. 4;

FIG. 7 is a side elevational view of FIG. 4; and

FIG. 8 is a rear elevational view of FIG. 4.

The stippling shown in FIGS. 1, 2 and 3 of the drawing illustrates opaqueness.

I claim:

The ornamental design for a planetarium, substantially as shown and described.
